The Munising Paper Company, Chicago, Ill., a
corporation of Ohio

Application September 19, 1947, Serial No. 141,493

Term of patent 3½ years

(Cl. D92—1)

To all whom it may concern:

Be it known that I, Frederick A. Foord, a citizen of the United States, residing at New York city, in the county of New York and State of New York, have invented a new, original, and ornamental Design for a Textile Fabric or the like, of which the following is a specification, reference being had to the accompanying drawing, forming part thereof.

The figure is a plan view of a portion of a textile fabric or the like showing my new design. The design unit is outlined by broken lines and is repeated vertically on the drawing.

I claim:

The ornamental design for a textile fabric or the like, substantially as shown and described.

FREDERICK A. FOORD.
